WILLIAM J. MARSHALL, OF NEWARK, NEW JERSEY, ASSIGNOR TO H. MAIMIN COMPANY, INC., A CORPORATION OF NEW YORK.

CLOTH-CUTTING MACHINE.

1,307,561.

Specification of Letters Patent. Patented June 24, 1919.

Application filed February 21, 1919. Serial No. 278,540.

To all whom it may concern:

Be it known that I, WILLIAM J. MARSHALL, residing at Newark, in the county of Essex, State of New Jersey, have invented 5 certain new and useful Improvements in Cloth-Cutting Machines; and I do hereby declare the following to be a full, clear, and exact description of the invention, such as will enable others skilled in the art to which 10 it appertains to make and use the same.

This invention relates to cloth-cutting machines, and more particularly involves an improved arrangement for holding the knife guard attachment and the stripper foot 15 structure carried thereon in any desired position of adjustment, while permitting the position of these parts to be quickly and easily altered according to the requirements of the work being performed by the machine. 20

It is the usual practice in machines of the reciprocating knife type to mount the knife guard attachment on a support which is slidably mounted on a guide or track attached 25 to the machine and to provide a thumb screw for clamping the support in any desired position of adjustment. Since the knife guard carries at its lower end the stripper foot structure which is adapted to press down on 30 the pile of fabric being cut to prevent the same from clinging to and rising with the reciprocating knife on its up strokes, it is necessary to make frequent changes in the position of the knife guard, these changes 35 being usually required at the beginning and end of each cutting operation and frequently even during the progress of the cutting operation in order to produce the proper pressure upon the pile of goods. The thumb 40 screw usually provided for holding the knife guard support possesses the disadvantages that it may become unscrewed from the machine and be lost, and even when in place its manipulation requires an appreciable 45 time, and if performed frequently, as is necessary in the use of the machine, the amount of time lost in setting the thumb screw will interfere with the performance of the work and cause a consequent diminution 50 of the efficiency of the machine. Furthermore the continual clamping of the screw against the guide or track will in time wear the face of the latter, and the worn portion will take usually the form of a roughened 55 groove which may finally assume such a

shape as to interfere with the proper gripping action of the screw. Frequent manipulation of the screw also wears its threads and the coöperating threads of the support so that the screw loses its grip, and the machine must be repaired by the replacement of the worn or damaged parts. 60

It is an object of this invention to overcome these defects of prior machines, by providing a construction in which the knife 65 guard support may be held in any desired position of adjustment by a clamp which is simple in construction and positive in action, may be quickly and easily manipulated and has no parts which may become accidentally 70 detached or appreciably damaged by wear.

The particular nature of the invention, as well as other objects and advantages thereof, will appear more clearly from a description 75 of a preferred embodiment as shown in the accompanying drawings, in which—

Figure 1 is a side elevation of a cloth cutting machine of a well-known type with the invention applied thereto;

Fig. 2 is a front elevation of the machine; 80

Fig. 3 is a central vertical section through the knife guard support and the clamp;

Fig. 4 is a view of the same parts in section along the line 4—4 of Fig. 3; and

Fig. 5 is a transverse section along the line 85 5—5 of Fig. 3.

In the drawings, in which similar reference characters denote similar parts throughout the several views, 10 denotes the base plate of the machine having attached thereto an upright standard 11 on which is mounted a motor 12 for reciprocating the knife 13, a handle 14 being provided for guiding the machine through the fabric to be cut. As is customary in machines of this 90 type, there is a pair of knife guard members 15 each carrying at its lower end a stripper foot member 16, the last named members being adapted to be fastened together by a clamp 17. Each of the knife 100 guard members is pivotally attached to a support 18 slidably mounted on a track or guide 19 attached to the front of the machine. Each knife guard member has associated therewith at its pivot a gear 105 wheel 20, these wheels meshing with each other and being connected by a spring 21 attached to projecting pins 22. The spring is so arranged that when the knife guard members occupy their normal position par- 110

allel to the knife, the spring lies below the pivots of these members, but when they occupy a raised position as shown in dotted lines in Fig. 2, the spring occupies a position above the pivots of the knife guard members so that these members are retained in lifted position.

In accordance with the present invention, the support 18 is provided with a transverse recess 23, the bottom of which is substantially flush with the face of the track 19. This recess is adapted to receive a casing 24, the outer portion 25 of which is formed with depressed portions indicated at 26, thus imparting to the casing a shape which permits it to be conveniently gripped between the thumb and fingers. The body of the casing is provided with a slot as at 27 and in each side of the slot is an inclined groove 28. These grooves are opposite each other and thus form a channel for the reception of a ball 29. The portion 25 of the casing is provided with a cylindrical socket 30 for a purpose which will hereinafter appear.

For producing the clamping action of the ball there is provided a movable member 31 having a shank portion 32 adapted to fit within the base of the slot 27 and provided with an inclined rear face as shown at 33 in Fig. 3. The shank portion also has a projection 34 extending therefrom at the bottom of the inclined face and terminating adjacent the face of the track 19. The member 31 is also provided with a stud 35 fitting within the socket 30 and surrounded by a spring 36 seated within the socket and tending to force the member 31 downwardly. A slot 37 is formed in the support 18 at right angles to the lower edge of the transverse recess within which the casing 24 is fitted. The projection 34 fits within this slot and by engagement with the bottom thereof limits the downward movement of the member 31 under the influence of the spring 36.

The machine described above is operated in the usual manner by pushing it through the pile of goods to be cut while the knife is being reciprocated by the motor. During the cutting operation, the members of the knife guard occupy their normal position with the stripper foot compressing the pile of goods with the required pressure. The knife guard members and their support 18 are held in place upon the track 19 by the clamp described above which functions as follows:

Under the influence of the spring 36, the member 31 is forced downwardly, and the inclined or wedging face 33 of the shank 32, in co-action with the channel in which the ball 29 is mounted, causes the latter to be wedged tightly against the face of the track 19 thereby preventing movement of the support 18 with respect to the track and hold-

ing the knife guard and stripper foot members in the desired position of adjustment. 65

Whenever it is desired to alter the position of the knife guard to adjust the stripper foot upon the pile of goods to be cut, or for any other reason, the member 31 is raised against the action of the spring 36 to release the ball 29 from clamping position, and as the member 31 is lifted the projection 34 will engage the ball to lift it in its channel until it is entirely out of contact with the face of the track 19. As soon, however, as the member 31 is released the ball will immediately be brought into clamping relation with the track to hold the parts in position. 70

It will thus be seen that the present invention provides a simple arrangement by which the knife guard members may be quickly set in any desired position of adjustment. The movement necessary to be imparted to the member 31 to overcome the spring and release the ball is in the same line as the movement of the support 18 along the track 19 so that the device may be conveniently manipulated by seizing the member 31 and the projecting portion 25 of the casing between the thumb and a finger, and after releasing the ball by lifting the member 31, the support 18 may be raised or lowered until it assumes the desired position. 75

As soon as the support has been set, the member 31 will be released, whereupon the mechanism instantly functions to clamp the support on the track. The time required for manipulation of the clutch is but momentary, and even when it is necessary to make frequent changes in the position of the knife guard members, the total time consumed will not amount to an appreciable period. There are no parts of the device which may become detached or possibly lost, and repeated contact of the ball against the face of the track will not produce any considerable wear thereon as is likely to occur if a set screw is used. 80

While the invention has been shown applied to one type of cloth cutting machine, it will be understood that it is equally applicable to machines of other types, and that various changes may be made in the details of construction without departing from the principle of the invention as defined in the appended claims. 95

I claim:

1. In a cloth cutting machine of the kind described, the combination of a track, a support slidably mounted on the track, knife guard members pivotally mounted on the support and carrying stripper foot members at their lower ends, a casing detachably secured to the support and provided with opposite inclined grooves forming a channel, a ball mounted in the channel formed by the grooves, a member slidably mounted in the

- casing and provided with an inclined portion adapted to coöperate with the ball to clamp it in the channel in engagement with the face of the track, the member being provided with an extension below the inclined portion for lifting the ball in the channel, and a spring adapted to act upon the member to hold the same in position to normally force the ball into engagement with the face 10 of the track to retain the support in any desired position of adjustment thereon.
2. In a cloth cutting machine of the kind described, the combination of a track, a support slidably mounted on the track, knife guard members pivotally mounted on the support and carrying stripper foot members at their lower ends, the support being provided with a transverse recess and a slot extending at right angles to one edge of the recess, a 20 casing fitting within the recess and detachably secured to the support and provided with a socket and opposite inclined grooves forming a channel, a ball in the channel, formed by the grooves, a member slidably mounted on the support and having a shank extending within the casing and provided with an inclined edge adapted to coöperate with the channel in holding the ball in engagement with the face of the track, the 25 slidable member also having a projection extending through the slot in the support and terminating adjacent the face of the track for lifting the ball in the channel, a stud associated with the slidable member and extending within the socket, and a spring 35 within the socket and surrounding the stud for normally forcing the slidable member out of the casing to hold the ball in clamping relation with the face of the track.
3. A clamp comprising a casing provided with a socket and a slot having inclined grooves in its opposite sides forming a channel, a ball in the channel formed by the grooves, a member slidably mounted on the support and having a shank extending within the slot in the casing and provided with an inclined edge adapted to coöperate with the channel in holding the ball in engagement with an external surface, the slid- 40 able member being provided with a projec- 45 tion extending at right angles to the shank at the base of the inclined edge thereof and adapted to lift the ball in the channel when the inclined edge is out of engagement with the ball, a stud associated with the member 50 and extending within the socket, and a spring within the socket and surrounding the stud for normally forcing the member out of the casing to hold the ball in clamping relation with the external surface. 55
